Primary Examiner — Ricky Pham

(74) Attorney, Agent, or Firm — Rumit Ranjit Kanakia

(57) **CLAIM**

The ornamental design for a aluminum foil pan, as shown and described.

DESCRIPTION

FIG. 1 is a perspective view of a aluminum foil pan, showing the first embodiment of my new design;

FIG. 2 is another perspective view thereof;

FIG. 3 is a front elevational view thereof, the rear elevational view, the left side view and the right side view are identical;

FIG. 4 is a top plan view thereof;

FIG. 5 is a bottom plan view thereof;

FIG. 6 is a perspective view of a aluminum foil pan, showing the second embodiment of my new design;

FIG. 7 is another perspective view thereof;

FIG. 8 is a front elevational view thereof, the rear elevational view, the left side view and the right side view are identical;

FIG. 9 is a top plan view thereof; and,

FIG. 10 is a bottom plan view thereof.

1 Claim, 10 Drawing Sheets
